SPRAYING DEVICE FOR HOT ROD MILL REELS

Charles J. Brown, Donora, and Harvey B. Trott,
McKeesport, Pa.

Application April 11, 1933. Serial No. 665,598

6 Claims. (Cl. 266—6).

This invention relates to improvements in spraying devices for hot rod mill reels.

In the manufacture of wire rods, suitably heated billets are continuously reduced, by being passed through a series of roll stands, and are reeled, while still in a highly heated condition. Reels used for this purpose rotate at a relatively high rate of speed, and are known in the art as "pouring" reels. It has been found that if the hot rods were sprayed with water, or other suitable liquid, a great deal of the scale on the hot rods would be loosened, which would facilitate its complete removal by acid pickling in a subsequent operation.

One object of the present invention is to provide a novel liquid spraying device for spraying rods while they are being "poured" on a conventional hot rod mill reel, the spray originating from the center of the coil so that centrifugal force will throw the water into and through the coil, and steam being generated which envelops the coil during cooling.

Another object of the invention is to provide a novel spraying device for hot rod mill reels which can be easily and quickly placed into and out of operative relationship with respect to the reel, in such manner as not to interfere with the stripping of the coiled rod from the reel.

These and further objects will appear after referring to the drawings, in which:

Figure 1 is a side elevation of the apparatus of the invention as associated with a conventional hot rod mill reel, which is shown in section.

Figure 2 is an end elevation of the apparatus, showing the hot rod mill reel and part of its associated "pusher" mechanism in section.

Referring more particularly to the drawings, the numeral 2 designates a conventional hot rod mill reel tub. A conventional "pouring" reel is disposed in the reel tub 2, and comprises a rotary base 3, which is provided with a centrally disposed hydraulically-actuated vertically movable shaft 4. A disk 5 is journaled on the upper end of the vertically movable shaft 4 and is provided with a number of suitable apertures to receive the guides 6 which are mounted on the rotating base 3 of the reel. Rotation of the base 3 will, of course, rotate the guides 6 and the disk 5. A suitable tube from the last roll pass of the rod mill will direct the hot rod to a suitable aperture in the tub 2 and thence to the reel.

A support 7 is disposed adjacent the upper portion of the reel tub 2, and is provided with a shaft 8 journaled therein, the latter being associated with a hydraulic cylinder (not shown). A hori-

zontal supporting arm, generally indicated at 9, is secured to the upper end of the shaft 8 and is provided with a cover 10 for closing the top of the reel tub 2. A vertically disposed plate 12 is secured to the horizontal supporting arm 9 in any suitable manner, and is provided with journals 13^a and 13^b at its upper and lower ends, respectively. A pipe 14 is disposed in the journals 13^a and 13^b and adapted for movement relative to the vertically disposed plate 12.

The pipe 14 carries a spray-head 15 at its lower end, and a connection 16 at its upper end which is connected with a supply hose 17. The supply hose 17 is connected at its other end to a suitable joint 18 mounted on the upper end of the shaft 8. A sleeve 19 is connected to the connection 18 at one of its ends and to a liquid supply hose 20 at its other end. A suitable liquid supplying conduit 21 and valve 22 supply the hose 20. A valve 23 is positioned between the sleeve 19 and connection 18, and is provided with an operating arm 24. The upper end of the shaft 8 is provided with a pivot 25, on which there is mounted, in an offset manner, a lever 26. The lever 26 carries a link 27 adjacent one of its ends for actuating the operating arm 24 for the valve 23, and also a link 28 which is connected to a weight 29. The weight 29 rests on a suitably disposed platform 30. A safety trip 31 is mounted on the platform 30 for operative association with a safety trip lever 32, which is carried on the lever 26 adjacent the pivot 25.

A link 33 is connected to the other end of the lever 26 and at its other end to a collar 33^a which is secured to the pipe 14.

A trip trigger 34 is pivoted to the support 7 and provided at one of its ends with a treadle 35, and at the other of its ends with a latch 36, the latter being adapted to seat in a cooperating recess 37 in the shaft 8.

In operation, while the hot rod is being delivered and coiled on the disk 5 of the "pouring" reel, the horizontal supporting arm 9 of the spraying device will be in its lowermost position, the shield 10 resting on the uppermost edge of the reel tub 2 and the spray-head 15, on the pipe 14, in its lowermost position.

Water or other suitable liquid is delivered by the supply pipe 21 through the valve 22, hose 20, valve 23, hose 17 and pipe 14 to the spray-head 15.

In practice, spraying continues for a short period of time after the rod, which is shown at A, is completely coiled, in order to give the spraying liquid sufficient opportunity to reach the 110

outer convolutions of the coil. After the rod has been completely sprayed, the treadle 35 is depressed, removing the latch 36 from the recess 37 which permits a hydraulic cylinder (not shown) 5 to raise the shaft 8 and its attached horizontal supporting arm 9 upwardly, the tub cover 10 moving with the horizontal support.

The counterweight 29, which is connected to one end of the lever 26, will act to rapidly elevate the pipe 14 through the link 33 and the collar 33^a which is secured to the pipe. This rapid elevation of the pipe 14 and its attached spray-head 15 is greater than the rate of elevation of the horizontal supporting arm 9 and the cover 10, and will cause the spray-head to move to a position adjacent the bottom of the cover. While the pipe 14 is being elevated, the lever 26 will act to draw the link 27 downwardly, and also the operating arm 24 for the valve 23 to which it is connected, and cut off the liquid supply.

A coil pusher 40 is mounted on a shaft 41 which is associated with a hydraulic cylinder 42. A lever 43 is pivoted on the cylinder 42, and carries a catch 43^a for restraining the coil pusher 40 and an extension 43^b for tripping the catch. The catch 43^a is released during the upward movement of the tub cover 10 by the contact of the extension 43^b with a trip 19^a which is mounted on the cover. When the disk 5 has been elevated to a position flush with the top of the tub 2 the pusher 40 is actuated and the coiled rod A is removed.

After the coil pusher has been retracted to inoperative position the hydraulically elevated shaft 4 is lowered, carrying with it the disk 5. The horizontal supporting arm 9 is also lowered, together with the tub cover 10, pipe 14 and spray-head 15, and the latch 36 seated in the recess 37 in the shaft 8. The coil pusher 40 will be held in operative position by the catch 43^a during the next reeling and spraying operation.

It is to be understood that the reel and its associated pusher mechanism are conventional, and as such form no part of the present invention other than in combination.

While we have shown and described one specific embodiment of our invention, it will be understood that we do not wish to be limited exactly thereto, since various modifications may be made without departing from the scope of our invention, as defined in the following claims.

We claim:

1. In combination with the reel of a hot rod mill, a vertically movable support adjacent said reel, a horizontal supporting arm secured to said support, and a spraying device connected to said arm and adapted to spray liquid through the convolutions of a coil being formed on said reel.
2. In combination with the reel of a hot rod mill, a vertically movable support adjacent said reel, a horizontal supporting arm secured to said support, a cover for said reel secured to said arm, and a spraying device connected to said arm and adapted to spray liquid through the convolutions of a coil being formed on said reel.
3. In a hot rod mill, a reeling tub, a reel disposed in said tub, means for elevating a coil

formed on said reel, means for removing said elevated coil, in combination with means for spraying liquid through the convolutions of said coil while it is being formed, a cover for said tub, means for raising said cover, and means for raising said spraying means relative to said reel and to said cover.

4. In combination with the reeling tub of a hot rod mill, a vertically movable support adjacent said tub, a horizontal supporting arm secured to said support, a cover for said tub secured to said arm, a pipe slidably associated with said horizontal supporting arm and extending below said cover, a spray-head on the lower end of said pipe, means associated with said vertically movable support for supplying liquid to said pipe, a valve for said liquid supply means, a link secured to said pipe, a lever pivoted on said vertically movable support and connected at one of its ends to said link, an operating lever for said valve and a counterweight connected to the other end of said lever, and means for elevating said vertically movable support.

5. In a hot rod mill, a reeling tub, a reel disposed in said tub, means for elevating and removing a coil formed on the reel in said tub, in combination with a vertically movable support adjacent said tub, a horizontal supporting arm secured to said support, a cover for said tub secured to said arm, a pipe slidably associated with said horizontal supporting arm and extending below said cover, a spray-head on the lower end of said pipe, means associated with said vertically movable support for supplying liquid to said pipe, a valve for said liquid supply means, a link secured to said pipe, a lever pivoted on said vertically movable support and connected at one of its ends to said link, an operating lever for said valve and a counterweight connected to the other end of said lever, a platform for said counterweight adjacent said vertically movable support, a trip arm secured to said pivoted lever, and a catch for said trip arm secured to said platform.

6. In a hot rod mill, a reeling tub, a reel disposed in said tub, means for elevating and removing a coil formed on the reel in said tub, in combination with a vertically movable support adjacent said tub, a horizontal supporting arm secured to said support, a cover for said tub secured to said arm, a pipe slidably associated with said horizontal supporting arm and extending below said cover, a spray-head on the lower end of said pipe, means associated with said vertically movable support for supplying liquid to said pipe, a valve for said liquid supply means, a link secured to said pipe, a lever pivoted on said vertically movable support and connected at one of its ends to said link, an operating lever for said valve and a counterweight connected to the other end of said lever, a platform for said counterweight adjacent said vertically movable support, a trip arm secured to said pivoted lever, a catch for said trip arm secured to said platform, a lock for holding said vertically movable support in its lowermost position, and means for releasing said lock.

CHARLES J. BROWN.
HARVEY B. TROTT.
